UNITED STATES PATENT OFFICE.

DAVID F. CRAWFORD, OF PITTSBURGH, PENNSYLVANIA.

LOCOMOTIVE-STOKER.

1,083,432.

Specification of Letters Patent.

Patented Jan. 6, 1914.

Application filed April 3, 1909. Serial No. 487,616.

To all whom it may concern:

Be it known that I, DAVID F. CRAWFORD, a citizen of the United States, residing at Pittsburgh, in the county of Allegheny and State of Pennsylvania, have invented certain new and useful Improvements in Locomotive-Stokers, of which the following is a specification.

The invention relates to locomotive stokers and particularly to those employing an underfeed. The invention has for its primary objects; the provision of an arrangement whereby a more uniform distribution of fuel over the grates is secured; and the provision of an arrangement of grates wherein the flue sheet is protected from wide variation in temperature and consequent injurious strains due to the operation of the drop grate and wherein the drop grate is readily accessible without removing the contents of the furnace. One embodiment of the invention is illustrated in the accompanying drawings, wherein:

Figure 1 is a horizontal section through one half of the fire-box above the grates.

Figure 2 is a vertical section through the center of the fire-box,

Figure 3 is a two part vertical section on the lines III—III of Figure 2, and Figure 4 is a section on the line IV—IV of Fig. 1.

As the invention resides particularly in the furnace, only so much of the locomotive structure is shown as is necessary to indicate the relation of the furnace parts thereto, and with respect to the showing in Figure 1, it will be understood that the other half of the furnace is substantially the same as the half shown. The principal parts shown may be enumerated as follows, 1 is the fire-box, which may be of any approved form; 2 is the underfeed trough extending into the center of the furnace, and gradually decreasing in depth as indicated most clearly in Figure 2; 3 is the feed casing to the rear and below the door 4 into the furnace, which casing is provided with the hopper 5 for the reception of fuel; 6 is the feed piston mounted for reciprocation in the casing 3; 7 is the operating cylinder for the feed piston, which cylinder is mounted upon the side of the fire-box; 8 is an agitator mounted for reciprocation in the bottom of the trough 2 and carried by the rod 9; 10 are the side grate bars mounted for rotation in sockets formed in the framework of the furnace as

indicated in Figure 3; 11 is a grate bar mounted at the front end of the feed trough, and also adapted to be rotated; 12 is one of the drop grates located at the extreme rear end of the furnace (Figure 1); 13 is an air chamber located adjacent the trough (Figure 3) and provided with inwardly directed twyers 14² for supplying air to the fuel in the trough; and 14 is a pipe leading from a suitably located floor for supplying pressure to the chamber 13.

The rock or grate bars 10 and 11 are provided with projecting fingers 14¹ and have at their ends downwardly projecting operating arms 15 (Figure 2), which arms are pivoted at their lower ends to the connecting rod 16 which is pivoted at its rear end to the rod 16¹ connected to the operating handle 17. These bars are downwardly inclined from their inner to their outer edges as indicated in Figure 3, which arrangement has been found to promote the proper spreading of the fuel to the outer edges of the furnace. The drop grates 12 are also rearwardly inclined as indicated in Figure 2, the purpose here also being to provide for a more ready movement of the fuel toward the rear end of the furnace. Experience has indicated that the tendency of the fuel is to collect at the center of the furnace leaving the sides and rear of the grate with insufficient fuel, and by the arrangement above described this tendency is to a large extent over-come and a proper distribution of the fuel is secured. The cylinder 7 is provided with a hollow piston 17¹ which is connected to the rock shaft 18 by means of the connecting rod 19 and crank arm 20. The feed piston 6 is operated from this rock shaft 18 by means of the crank arm 21 and connecting rod 22 (Figure 2). The agitator rod 9 is also operated from the rock shaft 18 by means of the crank 23 and connecting rod 24.

The placing of the drop grate 12 at the rear of the side grate instead of at the front thereof constitutes one of the features of my invention, and is advantageous in that this grate is removed from proximity to the flue sheet at the front end of the furnace, and the operation of the grate in dumping will not therefore expose the flue sheet to the sudden cooling which occurs in the ordinary type of construction when the drop grate is operated. This sudden change of temperature at the front of the

flue sheet produces considerable strain incident to the contraction of the metal, and as a result leakage is constantly occurring at this point. The drop grate is also more accessible at the rear end of the furnace than at the front thereof, and in case of a displacement or sticking of the grate it may be readily attended to and remedied without the necessity of removing all the fuel 5 from the furnace, as is the case where the drop grate is located at the front of the furnace and sticking thereof or displacement occurs. Other advantages incident to the construction will be apparent to those 10 skilled in the art.

The drop grate 12 is pivoted at 25 as indicated in Fig. 4, and is operated by the toggle links 26 and 27 pivoted together with a rule joint at 28, and engaged by the fork 20 29 carried by the bar 30. The bar 30 is reciprocated by the lever 31.

It will be apparent that the invention is applicable to locomotive furnaces employing various types of underfeed mechanism, 25 and that the feature of a rear drop grate is not limited in use or utility to a construction employing a single feed trough or to a construction in which such drop grate is at the side of the furnace, the only requirement 30 being that the drop grate be placed to the rear of the furnace and away from the flue sheet as opposed to the construction heretofore employed having the drop grates at the front end of the furnace.

Having thus described my invention and 35 illustrated its use, what I claim as new and desire to secure by Letters Patent is the following:—

1. The combination with a locomotive furnace, of an underfeed trough extending longitudinally of the furnace, a grate extending along the side of the trough, and substantially parallel to the side wall of the furnace, and comprising a main portion consisting of a series of rock bars extending to the 40 front end of the furnace, and a drop grate portion to the rear of the main portion forming a continuation thereof and lying adjacent the rear end of the furnace, the said drop grate being pivotally supported adjacent one edge on a line at right angles to the axis of the trough and adapted to swing about such pivotal support. 50

2. The combination with a locomotive furnace, of an underfeed trough extending into 55 the furnace, a grate extending along the side of the trough, and a rearwardly inclined drop grate located at the rear end of the furnace and extending transversely of the said grate. 60

In testimony whereof I have hereunto signed my name in the presence of the two 65 subscribed witnesses.

DAVID F. CRAWFORD.
